[57] CLAIM

The ornamental design for an ink tank for printer, as shown and described.

DESCRIPTION

FIG. 1 is a front elevational view of an ink tank for printer showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view thereof.

1 Claim, 1 Drawing Sheet

FIG. 1   *FIG. 2*   *FIG. 3*   *FIG. 4*

FIG. 5   *FIG. 6*   *FIG. 7*

UNITED STATES PATENT AND TRADEMARK OFFICE
CERTIFICATE OF CORRECTION

PATENT NO. : Des. 377,371

DATED : January 14, 1997

INVENTORS : HIROYIKI TOKUDA ET AL.

It is certified that error appears in the above-identified patent and that said Letters Patent is hereby corrected as shown below:

Title page, item
